Application December 19, 1932, Serial No. 647,909
In Canada March 19, 1929

31 Claims. (Cl. 24—153)

The invention relates broadly to fasteners, and more particularly to fasteners for binding loose papers together in a file, comprising a base having tongues or prongs at its ends adapted to extend over and be held bent down against a keeper or compressor.

An object of the invention is to provide an improved fastener of the character referred to with a novel keeper for holding the tongues in binding engagement therewith against the papers in a file.

Another object is to provide a paper fastener with a novel keeper, having improved means cooperating with one tongue, arranged to draw or clamp the papers together prior to bringing the other tongue into its final co-operative position.

Another object is to reduce the number of moving parts, in a paper fastener of the sliding lock type, and thereby reduce the cost of manufacture, simplify its mode of operation, and provide a more efficient product.

The foregoing and such other objects of the invention as will appear hereinafter as the description proceeds will be more readily understood from a perusal of the following specification, reference being had to the accompanying drawings, in which:

Fig. 1 is a perspective view of a fastener embodying features of the invention.

Fig. 2 is a longitudinal sectional view of the fastener of Fig. 1, showing the lock positioned over the bent down tongue.

Fig. 3 is a longitudinal sectional view of a modified form of keeper, shown attached at one end to a tongue.

Fig. 4 is a plan view of the keeper shown in Fig. 3.

Fig. 5 is a transverse sectional view of the keeper taken on line 5—5 of Fig. 3.

Fig. 6 is a plan view of a modified form of keeper.

Referring particularly to Figs. 1 and 2 of the drawing, the fastener constituting the preferred embodiment of the invention, comprises a base 10, provided at its ends with spaced tongues 11, adapted to pass through similarly spaced apertures 12 in the file of papers 13. Preferably, the tongues 11 are substantially less in width than the body of said base and are struck up substantially at right angles thereto, as shown.

The base 10 normally is positioned to lie flush against the bottom of the file papers 13, and a keeper 14 is adapted to be placed in co-operative position with the base against the top of the file papers. When in this position, the keeper and

the projecting ends of the tongues are in position to co-operate to bind the papers securely.

The keeper 14 preferably consists of an elongated strip of stiff material formed with an upset or shoulder 15 at one end and an elevated transverse strap 16 adjacent said upset. A transverse aperture 17 preferably is provided adjacent the other end of the keeper between parallel tracks 18 which extend longitudinally inwardly and outwardly from said aperture. 10

The tracks 18 preferably are struck up from the keeper in the form of ribs and have their ends 19 curved outwardly toward the longitudinal edges of the keeper to provide stops for a lock 21 mounted thereon for movement inwardly and outwardly over the aperture 17. As shown, the lock or latch 21 preferably consists of a strip of material having its ends bent under the marginal flanges 22 which are elevated from the plane of the bottom of the keeper to allow free sliding of the lock without its ends catching in or tearing the papers.

In operation, the keeper is placed with the strap 16 over one of the tongues said tongue being at right angles to the file papers and then swung 25 downwardly against the file of papers at which time the other tongue passes through the aperture 17. With the keeper now flat against the papers, the projecting end of the tongue extending through aperture 17 is bent down over the 30 keeper, between tracks 18 and the lock 21 is moved over the bent down tongue to retain it in place. It will be noted that said tongue may be bent down inwardly or outwardly of the aperture 17 and locked, the lock 21 being slidable 35 inwardly or outwardly of said aperture. It is preferable that a suitable projection 11a be provided adjacent the end of the tongue that extends through aperture 17 to limit inward movement of the lock 21 from coming off the end of the 40 tongue when the bent over portion of the tongue is shorter than the inwardly extending portions of tracks 18, due to the binding of a relatively thick file of papers. If desired, a short tapered rib 11b for frictionally co-acting with the lock to 45 prevent accidental misplacement thereof while in binding position, may be provided.

The keeper is held tightly against the papers at the other end by reason of the upset or shoulder end 15 which serves as a cam in co-operation with 50 the tongue engaged thereby to draw the keeper and base together, against the papers.

In the form of fastener shown in Figs. 3, 4 and 5, the keeper is provided with longitudinal guides 23 formed by folding the marginal edges 55

of the keeper upwardly and inwardly. A slot 17b is provided at one end to receive one of the tongues 11 and the guides 23 are depressed as at 24 and 25, to limit movement of the lock 26, guided therein, to one end of the keeper. Said lock preferably is folded over the top of the guides, as at 26a, to hold it elevated. It is preferable that the tongues 11 be provided adjacent their ends with tapered ribs 11b to insure retention of the lock over the tongue. The guides at the other end of the keeper are of greater width to provide a longitudinal receptacle or sheath open at its end to receive the other tongue, as shown.

15. Fig. 6 shows a keeper having a receptacle at one end formed by upwardly struck opposed longitudinal parallel lips 21, to receive one of the tongues 11, and an aperture 17c adjacent the other end. The end of the other tongue passes 20 through the aperture 17c and is bent down inwardly against the keeper and sprung laterally to engage beneath a lip 28 on the keeper.

It can be readily understood that the fasteners shown in various embodiments in the accompanying drawing and described in detail in the foregoing specification, effect a tight clamping of the papers in the file and although exemplary embodiments are shown and described it is to be understood that the invention is to be in no way limited to the precise structures shown but is to embrace such structures as fall within the spirit of the invention and the scope of the appended claims.

I claim:

35. 1. In a paper fastener keeper, in combination, a tongue receiving guideway at one end running substantially in the plane of said keeper, means adapted to receive a tongue, and a lock adapted to confine said tongue when bent flat against said keeper

40. 2. In a paper fastener keeper, in combination, a tongue receiving guideway at one end running substantially in the plane of said keeper, a transverse perforation adjacent the other end adapted to receive a tongue, and a lock adapted to confine said tongue when bent flat against said keeper.

45. 3. A fastener comprising, in combination, an elongated keeper having a strap adjacent one end, a base having spaced tongues, one on each end, one of said tongues being adapted to overlie one end of the keeper and be inserted beneath said strap, the other tongue being adapted to be bent over the top of the keeper, and means retaining said last named tongue against said keeper.

50. 4. A fastener comprising, in combination, an elongated keeper having a transverse opening in a plane substantially at right angles to the plane of and adjacent one end of the keeper, a base having spaced tongues, one at each end, one of said tongues being adapted to overlie one end of the keeper and be inserted through said opening, the other tongue being adapted to be bent over against the top of said keeper to co-operate with the keeper to bind said tongue to said keeper.

55. 5. A fastener comprising, in combination, an elongated keeper having a transverse opening in a plane substantially at right angles to the plane of and adjacent one end of the keeper, a base having spaced tongues, one at each end, one of said tongues being adapted to be bent over one end of said keeper and extend through said opening, the other tongue being adapted to be

bent over against the top of the keeper, and means retaining said last named tongue to said keeper.

6. A paper fastener keeper comprising an elongated member having a tongue receiving receptacle lying substantially in the plane of said member, said receptacle terminating and opening upon one end of said member, and a slideable tongue locking member mounted on said elongated member.

10. 7. A paper fastener keeper comprising a plate member having an opening near one end, a sheath member secured to the other end to form an open end receptacle, and a slideable locking member mounted on the plate.

15. 8. A paper fastener keeper as described, comprising, a plate having an opening near one end, means at the other end forming a tongue receiving receptacle, and a movable locking member mounted on the plate.

20. 9. In a paper fastener keeper, a keeper plate, means forming a longitudinal passage opening upon one end of said keeper adapted to receive and confine to the other end of said plate a tongue engaging member slidably mounted on said plate.

25. 10. A paper fastener keeper as described comprising a plate, means at one end forming a tongue receiving receptacle, a slot adjacent the other end, and a related lock slidably mounted on the plate.

30. 11. A fastener comprising, in combination, an elongated keeper having a transverse strap adjacent one end, a base having spaced tongues one on each end, one of said tongues being adapted to be bent over said end and inserted under said strap, the other tongue being adapted to be bent down over the top of said keeper, and slideable means on said keeper adapted to engage and hold the last named tongue to the keeper.

35. 12. A fastener comprising, in combination, an elongated keeper having a transverse opening adjacent one end and a transverse strap adjacent the other end, a base having spaced tongues one on each end, one of said tongues being adapted to be bent over the keeper and inserted beneath said strap the other tongue being adapted to extend through said opening and be bent over said keeper, and means on the keeper adapted to co-operate with the last named tongue to bind said tongue over the keeper.

40. 13. A fastener comprising, in combination, an elongated keeper having an elevated strap adjacent one end, a base having spaced tongues one on each end, one of said tongues being adapted to be bent over the end of said keeper and inserted through said strap, the other tongue being bent over the top of said keeper, and means slideable on said keeper adapted to co-operate with said last named tongue to hold the tongue to the keeper.

45. 14. A fastener comprising, in combination, an elongated keeper, a flat elongated base having spaced tongues one on each end, a single strap formed inwardly of one end of said keeper and an aperture in the other end of said keeper, said strap being adapted to receive slideable thereunder one of said tongues, the aperture in the other end being adapted to receive the other of said tongues, said tongue being adapted to be bent down over the keeper, and a lock slideable on said keeper over the bent over portion of the said other tongue to hold it substantially parallel with the keeper.

50. 15. A fastener comprising, in combination, an elongated keeper having a transverse integral

strap struck up adjacent one end, a base having spaced tongues one on each end, one of said tongues being adapted to be bent over one end of the keeper and inserted beneath said strap, the other tongue being bent over the top of the keeper, and slide means retaining said last named tongue against said keeper.

16. A fastener comprising, in combination, an elongated keeper having a transverse aperture adjacent one end, and a narrow transverse strap forming openings at its opposed edges between it and the keeper adjacent the other end, a base having spaced tongues one on each end, one of said tongues being insertable over said keeper beneath said strap, the other of said tongues being adapted to extend through said aperture and be bent down over the keeper, and means on said keeper adjacent the end having the aperture to retain said tongue bent against the keeper.

17. A fastener comprising, in combination, an elongated keeper having a strap adjacent one end, a base having spaced tongues, one on each end, one of said tongues being adapted to overlie one end of the keeper and be inserted beneath said strap, the other tongue being adapted to be bent over against the top of said keeper, and means on the keeper adapted to co-operate with the tongue to bind said tongue to the keeper.

18. A fastener adapted to bind file papers together comprising, in combination, an elongated keeper, a flat elongated base having spaced tongues one on each end, said tongues being adapted to be inserted through apertures in said papers, a strap formed in one end of said keeper and an aperture in the other end of said keeper, said strap being adapted to slidably receive one of said tongues, the aperture in the other end being adapted to receive the other of said tongues, said other tongue being adapted to be bent over against the keeper, and a lock slidable on said keeper over the bent over portion of the tongue to hold it against the keeper, the strap co-operating with said tongue upon movement of the keeper to clamp the papers together at one end prior to the sliding of the lock over said bent over tongue.

19. A fastener comprising, in combination, an elongated keeper having a transverse aperture adjacent one end and a strap adjacent the other end, a base having spaced tongues one on each end, one of said tongues being bent over the keeper and inserted beneath said strap, the other of said tongues being adapted to extend through said aperture and be bent down over the keeper, longitudinal guides on said keeper, means slidable on said guides adapted to be moved over the bent down end of the last named tongue, and means on said tongue adapted to be engaged by the slidable means to retain it in place over said tongue.

20. A fastener comprising, in combination, a keeper having a strap at one end and an aperture at the other end, a base having spaced tongues one on each end, one of said tongues being adapted to engage said strap and be bent down over the keeper as said keeper is rotated downwardly, the other of said tongues being adapted to pass through said aperture as said keeper is rotated downwardly and then bent over the keeper, guides formed at one end of the keeper at opposite sides of the aperture and the associated tongue, a positive stop on the end of said associated tongue, a short rib on said tongue, and a lock on said keeper movable along said

guides over said rib to bind the associated tongue to the keeper.

21. A fastener having, in combination, a base provided with spaced tongues, a stop and short rib formed on one of said tongues, a keeper having means to engage said tongues, and a lock slidable along said keeper to engage said stop and rib, said engagement being a binding engagement with said rib and a positive stopping engagement with said stop.

22. In a fastener, a keeper comprising, a flat elongated member formed with substantially parallel side guides, a transverse shoulder at the end, and a strap adjacent said shoulder.

23. An article of the class described, having, in combination, a keeper provided with a strap at one end and an aperture at the other end, relatively short longitudinal runways formed in said keeper at both sides of said aperture, and a lock slidably mounted on said runways arranged to slide outwardly over and clear of said aperture and to be stopped thereby after passing said aperture.

24. An article of the class described, having in combination, a keeper with a shoulder at one end, a strap adjacent thereto and an aperture at the other end, relatively short longitudinal runways formed in said keeper at both sides of said aperture, and a lock slidably mounted on said runways arranged to slide outwardly over and clear of said aperture and to be stopped thereby after passing said aperture.

25. In an article of the class described, the combination of, a keeper, longitudinal opposed guide flanges extending inwardly along said keeper, said flanges extending inwardly a greater distance at one end than at the other end, an aperture adjacent said other end, and a lock mounted for sliding on said guides along said other end.

26. A fastener, comprising, in combination, an elongated keeper having longitudinal guides at one end and an aperture adjacent the other end, a base having tongues one at each end, one of said tongues being adapted to be bent over the keeper and inserted under said guides, the other of said tongues being insertable through said aperture and adapted to be bent over against said keeper, and means on said keeper to hold said bent over tongue over the keeper.

27. In an article of the class described, the combination of, a keeper having guides at one end opening inwardly and a perforation at the other end with a lock slidably mounted on said keeper arranged to slide outwardly over and beyond said perforation.

28. A fastener comprising, in combination, an elongated keeper having longitudinal guides at one end and an aperture adjacent the other end, a base having tongues one at each end, one of said tongues being adapted to be bent over the keeper and inserted beneath said guides, the other of said tongues insertable through said aperture and being adapted to be bent over said keeper, and a lock slidable along said keeper over said bent tongue to bind the latter against the keeper.

29. A paper fastener keeper as described comprising a metal plate having a longitudinal trough formed therein, a sheath plate secured to one end of the metal plate transversely of the trough, said metal plate having an opening adjacent the other end, and a locking member slidably mounted on the metal plate.

30. A fastener, comprising, in combination, a keeper having an aperture at one end, a base having spaced tongues one at each end, a lock formed on said keeper at said one end, a guide at the other end of said keeper adapted to receive one of said tongues, the other of said tongues being adapted to pass through said aper-

ture and be bent down against the keeper and held there by said lock.

31. A fastener having, in combination, a base provided with spaced tongues, and a keeper having a tongue receiving receptacle at one end and tongue engaging means formed at the other end.

DANIEL A. BRENNAN.
